DESIGN FOR AN ELECTROMAGNETIC RELAY OR SIMILAR ARTICLE

Carl H. Larson, Elkhart, Ind., and Daniel J.
McCarthy, Elgin, Ill.

Application November 2, 1935, Serial No. 59,347

Term of patent 14 years

To all whom it may concern:

Be it known that we, Carl R. Larson and Daniel J. McCarthy, citizens of the United States of America, and residents, respectively, of Elkhart, county of Elkhart, and State of Indiana, and Elgin, county of Kane, and State of Illinois, have invented a new, original, and ornamental Design for Electromagnetic Relay or Similar Article, of which the following is a specification, reference being had to the accompanying drawing, forming a part thereof, wherein

Fig. 1 is a perspective view of a relay embodying our design;

Fig. 2 is a front, elevational view;
Fig. 3 is a plan view; and
Figs. 4 and 5 are side, elevational views.
The electromagnetic relay shown in the accompanying drawing has a glass front which exposes a portion of the relay mechanism to view.

We claim:—

The ornamental design for an electromagnetic relay or similar article substantially as shown and described.

CARL H. LARSON.
DANIEL J. McCARTHY.
